RAILWAY TRUCK AND BODY
ORGANIZATION

Michael Watter, Philadelphia, Pa., assignor to
The Budd Company, Philadelphia, Pa., a corporation of Pennsylvania

Application December 30, 1947, Serial No. 794,569

1 Claim. (Cl. 105—199)

1

The invention relates to railway car rolling stock and, more particularly, to the truck and body organization.

It is among the objects of the invention to simplify such structures, to reduce their weight, to lessen the communicating of noises and high-frequency vibrations to the body, to cushion the relative movements between truck and body by a simplified cushioning means, to improve the riding qualities, and to make the parts readily accessible for servicing and repairing.

These and other objects and advantages and the manner in which they are attained will become apparent from the following detailed description when read in connection with the accompanying drawings forming a part of this specification.

In the drawings:

Figure 1 is a plan view of a truck structure according to the invention with parts broken away and shown in section;

Figure 2 is a side elevational view of the truck shown in Figure 1, when combined with a car body mounted thereon;

Figure 3 is a vertical longitudinal sectional view, on an enlarged scale, the section being taken substantially along the broken line 3—3 of Figure 1;

Figure 4 is a vertical transverse sectional view on the same scale as Figure 3, the section being taken substantially along the broken line 4—4 of Figure 1; and

Figure 5 is a horizontal transverse sectional view on the same scale as Figure 3, the section being taken substantially along the broken line 5—5 of Figure 4.

The truck according to the embodiment of the invention shown in the drawings is comprised of a simple frame, H-shaped when viewed in plan and designated generally by the numeral 10. This H-shaped frame includes the longitudinally extending side frame members 11, 11 and a central transverse interconnecting member 12 extending between the side frame members and rigidly connected thereto. The central portion of this member is offset downwardly, see Figure 4, to provide clearance for the body mounted on the truck and generally designated by numeral 13.

As shown in Figure 3, the member 12 is of generally T-, I- or other open-cross-section having a deep vertical web 14 interconnecting a top chord 15 and a bottom 16. It will be noted that the top chord is somewhat wider in section than the bottom chord and that the ends of these chords are widened where they are joined to the side frames but this is a particular embodiment and

5 may vary, for instance, by using corner tubular reinforcements. Such a transverse member is strong in tension and compression and in longitudinal shear so that it suffices to hold the side members in tram, but because of its open construction, it is sufficiently flexible in torsion to permit the side frame members to rotate slightly with respect to each other about a horizontal transverse axis, such rotation being desirable to 10 allow the wheels supporting the truck frame to follow the usual track irregularities.

The ends of the truck frame are supported by wheel and axle assemblies generally designated 17, these assemblies being flexibly connected to 15 the side frames, as by universal joint structures, not shown in detail herein, which permit limited tilting of the axles with respect to the side frames. Such movement may be restrained by rubber cushions (not shown) in the universal joints, which also dampen the shocks and avoid 20 transmission of high-frequency vibrations between the wheel and axle assemblies and the truck frame.

As shown, each wheel and axle assembly 17 is 25 comprised of a hollow fixed axle 18 connected by the above referred to universal joints to the respective side frames. A rotary axle 18', Figure 3, is suitably mounted, as by anti-friction bearings, interposed between the ends of the fixed axle and the rotary axle, this rotary axle extending outwardly beyond the side frames and carrying the 30 wheels 19 rigidly secured thereto adjacent its ends and just outboard of the side frames. If desired, the rotary axle may be split so that each wheel is free to rotate independently of the other.

35 The truck organization so far described lends itself readily to the provision of brakes arranged outboard of the frame where they are readily accessible for replacement or repair. Such brakes may comprise a rotary disc brake member 20 40 rotating with the adjacent wheel 19 and with which cooperating non-rotary brake means (not shown) mounted on a laterally projecting bracket 21 formed integrally with the end of the truck side frame 11. Such bracket is in this instance 45 shown arranged outwardly of the associated wheels and brake discs, but it will be understood that it could be arranged on the inward side of the wheel and brake disc, if desired, or may be used in connection with the customary clasp means. Where an anti-wheel slide device is 50 utilized as shown, the casing 22 for enclosing it may be rotatably mounted on the projecting reduced end of the rotary axle, and held against rotation by an arm 23, connected by a suitable rubber cushioned joint structure 24 to the adja-

cent side frame. Similar brake mechanism and anti-wheel slide arrestors may be provided at each wheel.

The car body, with the improved arrangement, is carried through spring means, designated generally by 25, directly by the side frames 11 of the truck between the longitudinally spaced wheels thereof. Such spring means are preferably of the pneumatic-cushion type which permit all relative movements between the car body and truck frame through deformation of the cushions. Since the load is carried directly by the truck side frames, and the springs are free to permit the necessary vertical, lateral and rotary movements between the car body and truck, it will be seen that the truck and car structure can be very much lightened and simplified over known constructions. The truck bolster, swing hangers and spring plank are all eliminated, and the car body bolster may also be materially lightened.

To attain these ends, the car body is supported at each side by a pair of longitudinally spaced pneumatic springs, each designated by numeral 26, these springs being of a known variety having flexible side walls 39 of suitably reinforced rubber or the like and having their ends secured to plates 27 and 28, see Figure 4, secured, respectively, to the car underframe and to the laterally widened top 29 of the truck side frames. While the drawings show but one such unit consisting of side walls 39 and plates 27 and 28 at each spring location, it will be understood that the showing is merely exemplary, and it is within the compass of the invention to use more than one such unit in superposed relation where more flexibility is desired. These spring units will be understood to contain air or other gas or fluid under compression and to be connected with an air or other gas or fluid reservoir to obtain the desired spring characteristics, as is well known in air springs. In fact, space for such a reservoir has been provided on the side frames of the truck as shown by the curved outline of the frame at 35, Figures 2, 4 and 5.

As clearly shown in Figure 4, each spring unit 26 has its bottom plate 28 seated on a flat-faced circular boss 32 on the side frame and is held from shifting laterally by a ring 33 secured to the plate and encircling the boss 32. The upper plate 27 has a circular recess thereon formed in this case by welding a ring 34 to the plate, and the lower flat face of a circular side bearing 35 secured to the car body bolster 36 seats therein, suitable wear and reinforcing plates 37 being provided between the side bearing face and the spring unit plate 37. With this arrangement, it will be seen that the spring units 26 may be readily located in place and/or removed by first lifting the car body off the truck.

At the same time, it will be seen that since each of the spring units is similarly mounted, all of them unite to participate in the lateral movement of the car body with respect to the truck, as well to permit such movement as is desirable in rounding curved track, by the deformation of the side walls of the units.

To avoid excessive lateral and vertical movements between the car body and the truck and to act as safety means, suitable stop means are provided. This stop means for each side frame comprises a stop abutment 37' secured to project above the truck side frame proper, see Figure 4, and faced on its top and its inner side with a rubber buffer 38. A stop bracket 39 having a V-

opening providing horizontal and vertical faces for engaging the top and inner side of the stop abutment 37' is secured in opposed relation thereto on the car body bolster 36 and provides safety in case of spring failure.

The air springs are also of sufficient yieldability in their side walls 39 to permit the limited distortion necessary to allow the usual swiveling movement of the truck with respect to the car body, without presenting excessive resistance.

Thus it will be seen that one and the same means, namely, the pneumatic springing cushions 25, cushion the relative vertical movements, 15 while permitting the relative lateral movements and the relative rotary movements between the truck and car body and at all times tend to return the parts to normal position after deformation of the cushions. Ease of riding is thus assured, since all minor vibrations are readily absorbed by the cushion springs.

Since the usual interfitting load-carrying center plates on truck and car body are omitted in this construction, suitable driving means has 25 to be provided between the car body and truck, but such means must be of a nature to permit the relatively free action of the pneumatic spring units 26 and the slight tilting of the side frames with respect to each other about a transverse axis. Such means is most clearly shown in Figures 3, 4 and 5. This means also provides a vertical axis about which the car body and truck turn relative to each other.

In the form shown, the car body center sill 35 48 has secured to it a recessed center plate 40' adapted to receive in said recess an upward projection 41 on a spider member 42 associated with the truck, these parts being preferably cushioned with respect to each other by a rubber cushion 30 43 between the bottom of the recess in center plate 40' and the top of the projection 41 and being held in assembled but relatively rotatable relation by a usual form of king pin, as 44.

The spider member 42 is connected to each side frame 11 of the truck by similar means. 45 Such means is arranged to impose limited restraint upon the relative vertical and lateral movements between the truck and car body but yet allow the pneumatic springs to function relatively freely in their intended manner, as described hereinbefore.

Since the driving means on opposite sides of the truck are similar, but one of these means need be described.

As shown in Figures 3 and 5, longitudinally spaced brackets 45 are rigidly secured to the inner face of the side frame member 11. These brackets carry large diameter bearings receiving tubular trunnions 46 between which and the respective 55 bearings are received the rubber bushings 47 suitably secured thereto as by vulcanizing. The adjacent ends of the trunnions 46 extend some distance beyond the respective bearings and to these ends are securely calmed the vertically extending arms 48. The upper ends of the arms 48 are provided with bearings 49 receiving trunnions 50 on the ends of a longitudinally extending beam 51 between the arms. The trunnions 50 are held in place by nuts screwed onto the projecting 60 screw-threaded ends thereof. Rubber bushings 52 are provided between the bearings 49 and their respective trunnions 50. The longitudinally extending beam has a central transverse opening therethrough providing spaced bearings 53, 53 in 70 75 which is mounted through rubber bushings 54, 54

a trunnion or shaft 55 secured in place by a washer and nut screwed onto its screw threaded end. The opposite end of this trunnion is integral with a sleeve 56 extending between bearings 57, 58 on the spider member 42. These parts are secured together by a bolt 58 passing through the bearings and sleeve and washers inserted between the ends of the respective bearings 57 and the head and nut of the bolt respectively. These bearings and the bolt are also spaced by rubber sleeves 59, 59.

It will be seen that by this arrangement a positive drive is obtained between the king pin 44 and the side frames 11 of the truck on each side of the truck, yet the means for providing this drive are restrained from following the relative vertical, lateral and rotary movements of the truck and car body only by the torsion of the rubber sleeves in the bearings. It will be noted that the rubber in most instances is vulcanized to two metal sleeves, which may be fitted into the bearings of the trunnions associated therewith so as to allow slipping without straining the rubber in case of excessive movement.

While a specific embodiment of the invention has been described herein, it will be understood that changes and modifications may be made by those skilled in the art without departing from the main features of the invention, and such changes and modifications are intended to be covered by the claim appended hereto.

What is claimed is:

A railway car and truck organization comprising a truck having longitudinally extending side frame members supported by wheels adjacent their ends, a transom interconnecting the side members centrally thereof, and a car body resiliently supported solely from the intermediate portions of said side members, said resilient sup-

port comprising hollow air cushions having flexible walls and being designed to provide for vertical springing movement between said body and truck and also limited relative lateral and rotary movements, by reason of the flexibility of the cushion walls, between said body and truck, and means flexibly connecting said truck and body to form a driving connection between them and restraining such lateral relative movements, and means including a perforated center plate on one of said truck and body, and a central perforated member on the other one of said body and truck mating with said center plate, said plate and member receiving a center pin loosely in the perforations thereof, whereby said means allows relatively free vertical springing movement between the body and truck frame while restraining excessive relative lateral movement therebetween.

MICHAEL WATTER.
